FLOW TUBE

Henry M. Unschuld, Chicago, Ill.

Application December 1, 1944, Serial No. 566,141

4 Claims. (Cl. 204—312)

1

The object of this invention is to provide a flow tube of new and useful construction for use in the treatment of fluids passing through the same.

While the foregoing statement is indicative in a general way of the nature of the invention, other more specific objects and advantages will be apparent to those skilled in the art upon a full understanding of the construction of the new tube.

A preferred embodiment of the invention is presented herein by way of exemplification but it will of course be appreciated that the invention is susceptible of incorporation in other structurally modified forms coming equally within the scope of the appended claims.

In the accompanying drawing,

Fig. 1 is a side view of a flow tube constructed in accordance with the invention;

Fig. 2 is a transverse section through the tube, taken on the line 2—2 of Fig. 1;

Fig. 3 is another transverse section, taken on the line 3—3 of Fig. 1; and

Fig. 4 is a view of the rear end of the tube.

The flow tube which forms the subject matter of this invention is an elongated open-ended conduit 10 which is preferably made in three telescopically associated sections 11, 12 and 13. These sections may be advantageously made of quartz glass.

The first section 11 is provided at its front end with a radially extending flange 14 for endwise connection with an associated conduit. The flange 14 contains a small centrally located opening 15 through which the fluid which is to be treated is adapted to enter. From the flange 14 the section 11 extends rearwardly in a small diameter neck portion 16 of somewhat larger inside diameter than the opening 15. The neck portion 16 opens into a larger diameter body portion 17 which contains a centrally arranged electrode carrier 18. At its rear end the first section 11 terminates in a rearwardly tapering portion 19 which sleeves into and is fixedly bonded with an oppositely tapered portion 20 on the front end of the second or intermediate section 12.

The electrode carrier 18 consists of a small tube 21 which encloses an electrical conductor 22. The tube 21, with the conductor 22 within the same, extends radially inward from one side of the body portion 17 to a point adjacent the center of that portion and then extends rearwardly to a point adjacent the rear end of the portion 17, the tube 21 being supported intermediate its ends by spoke-like formations 23 which extend radially from the same to the surrounding wall of the portion 17. The conductor 22 extends rearwardly

2

at 24 from the rear end of the carrying tube 21 and is provided beyond the rear end of the first section 11 with a ring-shaped electrode 25, which electrode is supported from the rear end of the conductor 24 in spaced concentric relation to the inner wall of the section 12 by radially extending spoke members 26. The electrode 25 is preferably of rearwardly diverging cross section, as shown.

10 The second or intermediate section 12 continues rearwardly from the rearwardly tapering connecting portion 20 into a body portion 27. The body portion 27 merges rearwardly into a bulbous portion 28 of somewhat larger diameter. Beyond 15 the portion 28 the section 12 contracts into a short cylindrical section 29 which terminates at its rear end in a rearwardly diverging portion 30, which last mentioned portion is sleeved over and fixedly bonded to a telescopically associated portion 31 of the third or last section 13.

15 The section 13 is provided at its front end with a rearwardly diverging portion 32 having a small centrally arranged opening 33. The portion 32 merges rearwardly into a cylindrical portion 34 20 which is encompassed by the portion 29 of the second section 12 and with a rearwardly diverging portion 35 which is encompassed by the rearwardly diverging portion 30 of the section 12. Between the portions 29 and 30 of the section 12 25 and the portions 34 and 35 of the section 13 a second ring-shaped electrode 36 is positioned, with the front edge 37 of the electrode projecting forwardly into the rear end of the annular space 38 present between the bulbous portion 28 of the 30 second section and the reduced front end 32 of the third section. This electrode is provided with a conductor 39 which extends to the outside of the tube.

35 Beyond the rearwardly diverging portion 31 the third section 13 is shaped to provide a cylindrical body portion 40 of substantial diameter in which a hollow tube 41 is coiled, preferably as shown. The two ends of the tube 41 are connected with nozzles 42 and 43 which are located on the outside of the section 13, preferably as integral portions of the latter. From the portion 40 the third section 13 is abruptly reduced in diameter at 44 and opens into a small diameter neck portion 45, of substantially the same size as the neck portion 16. The neck portion 45 terminates in a radial attaching flange 46 containing a small centrally located opening 47, preferably of smaller size than the neck portion 45.

45 The conductors 22 and 39 are adapted to be connected by leads 48 and 49 to a source of elec-

trical current, the nature of the current depending upon the character of the treatment to which the fluid flowing through the tube is intended to be subjected. The nozzles 42 and 43 are adapted to be connected with a circulating cooling medium, the character and temperature of the medium depending upon the temperature to which the fluid is to be reduced and also the rate of flow of the fluid.

Briefly described, the flow tube of this invention is designed to subject a gas or other fluid flowing through the same first to the bombarding action of an electrostatic field operating between the electrodes 25 and 31, and, immediately thereafter, to the cooling action of the medium flowing through the coil 41. The annular chamber formed within the second section 12 about the reduced front end 32 of the third section permits of the fluid being subjected to the action of the current in a semi-quiescent eddy zone, without however interfering with the continuous flow of the fluid through the tube from one end of the same to the other.

I claim:

1. A flow tube for use in treating fluid with electrostatic charges comprising a generally tubular glass member, a partition dividing said tubular member into two axially spaced chambers, connecting means on the ends of said tubular glass member for connecting the one end to a fluid supply line and the other end to a discharge line, a pair of spaced electrodes in the one of said chambers which receives the fluid to be treated, and a temperature controlling means in the other of said chambers, said dividing partition having walls forming a hollow truncated cone-shaped extension for said other chamber with the small end thereof extending within said fluid receiving chamber to a point between said electrodes and with the walls thereof spaced from the walls of said receiving chamber whereby the flow of the fluid in the receiving chamber is retarded and subjected to the electrostatic charges for a longer period of time.

2. A flow tube for use in treating fluids with electrostatic charges comprising a generally tubular member forming a treatment chamber, said member having means on one end for connecting the same to a fluid supply line and having its walls flared outwardly at its other end, another generally tubular member having means on one end for connecting the same to a discharge line and having the walls at its other end flared inwardly and terminating in a restricted opening, said tubular members being permanently connected in telescoped relation with the inwardly flared end walls of said second mentioned tubular member extending a substantial distance within said first mentioned tubular member to form a restricted passageway between the tubular members and to form within said treatment chamber an eddy zone for the fluid being treated, a pair of axially spaced electrodes one of which is positioned adjacent the entrance end of said treatment chamber and the other of which is positioned at the connecting line between said tubular members,

whereby fluid is held in said treatment chamber for a longer period of time by the action of said eddy zone and said restricted passageway, and temperature controlling means within said second mentioned tubular member.

5. An elongated flow tube through which a fluid is adapted to pass, entering at one end of the tube and leaving at the other, said tube containing a pair of spaced electrodes adapted for connection 10 exteriorly of the tube in an electrical circuit for subjecting the fluid upon entering the tube to an electrical action, a temperature controlling element immediately beyond the electrodes past which the fluid is adapted to flow, said tube comprising a plurality of relatively thin walled sections of quartz glass and a cone-shaped partition extending from the end of one of said sections adjacent one of said electrodes with the smaller end thereof positioned in the space between said electrodes and having a restricted aperture in said end.

15. An elongated flow tube through which a fluid is adapted to pass, entering at one end of the tube and leaving at the other, said tube having a pair of spaced ring electrodes therein, said tube comprising a plurality of relatively thin walled sections of quartz glass having end portions which are connected in telescoped relation, the section of said tube at the end through which the fluid enters having a relatively small passageway for receiving the fluid and a somewhat larger connecting passageway terminating in a constricted end which is telescoped within the flared end of the adjacent central section, means for 20 supporting one of said electrodes in said larger passageway, said electrode being positioned in the end of said adjacent central section, said central section having a bulbous portion terminating in a cylindrical portion which telescopes the adjacent end of the section at the discharge end of the tube, means for supporting the other electrode between the tube sections at the end of the bulbous portion, said last mentioned tube section having a truncated partition forming end 25 the smaller end of which extends a substantial distance into the bulbous portion of the central tube section and a communicating chamber of larger diameter and cooling coils mounted in said last mentioned chamber.
